TABULATING MECHANISM.

1,078,357.

Specification of Letters Patent. Patented Nov. 11, 1913.

Application filed March 6, 1911. Serial No. 612,710.

To all whom it may concern:

Be it known that I, HARRY LANDSIEDEL, a citizen of the United States, residing at Poplar Bluff, in the county of Butler and State of Missouri, have invented a new and useful Tabulating Mechanism, of which the following is a specification.

This invention relates to tabulating mechanisms for recording machines and is, broadly, a continuation and carrying forward of the invention constituting the subject-matter of my pending application for Letters Patent, filed December 2, 1909, Serial Number 530,949, showing the tabulating mechanism applied to a pin-carriage in an adding machine. The pin carriage in the adding machine, like paper carriages, is mounted on a support on which it is moved laterally by an escapement and motor device as the keys are operated, and may be moved any desired predetermined distance at one operation by adjustment and operation of the tabulating mechanism. In the present instance I have shown my invention embodied in a typewriting machine to control the paper-carriage, while in the said pending application my invention is embodied in connection with a pin-carriage which controls the recording of data within the capacity of that machine.

The object of the invention is to equip the carriage with a series of column stops whereby the carriage may be stopped in any desired position to receive the record, and convenient manipulative means for readily setting the different stops to conform to the forms or columns to be recorded, in combination with a device whereby the column stops may be "cleared" and caused to return to idle adjustment.

There are other objects to be attained by my invention, all of which will be apparent to those skilled in the art to which this invention pertains, without specific mention.

In the accompanying drawings I have illustrated the present embodiment of my invention, and in said drawings Figure 1 is a plan view of a typewriter frame, carriage and key-board having my tabulating mechanism embodied therein. Fig. 2 is a detail view, partially in section, showing the tabulating stops and the release device. Fig. 3 is a vertical sectional view of the paper-

carriage and tabulating mechanism, showing also the setting key and the tabulating key. Fig. 4 is a front elevation of a part of the paper-carriage. Fig. 5 is a detail view of lever whereby the tabulating pins are set. Fig. 6 is an enlarged horizontal sectional view of the frame or housing carrying the stops, and of the abutment against which the stops engage. Fig. 7 is a vertical sectional view of the step support and the abutment for the stops. Fig. 8 is a sectional view showing one tabulating stop up and another moving to upward adjustment.

The frame of the machine supports the transverse rails 1 upon which the carriage 2 is supported by anti-friction rolls 3, whereby the carriage is moved from side to side of the machine with slight frictional resistance. One of the rails is preferably provided with a groove 4, which receives one or more pins 5 attached to the carriage. The pin or pins 5 prevent derailment of the carriage when the tabulating stops are set. A platen 6 is mounted in the carriage 2 and is provided with the usual knobs 7 for manual rotation. A scale 8 at the visible side of the platen serves as a register to enable the operator to set the tabulating stops of the desired number and position and to this extent is an element of the machine with which my invention is co-operatively related. The carriage is actuated toward the left with respect to the operator by a suitable motor 9, the movement being controlled by an escapement 10, which is entrained with the carriage rack 11. The connections from the keys whereby the escapement is operated may be of any suitable arrangement and are not illustrated herein, since the form and arrangement of such connections are immaterial.

The carriage 2 supports a housing or frame 12 extending preferably from side to side and comprising two substantially parallel walls being, in the present instance, the upper and lower walls. In the present embodiment the support 12 is of sufficient width from front to back to have formed therein three transverse rows of slightly elongated holes 13 (Figs. 6 and 7). The holes of the different rows are staggered as clearly shown in Figs. 2 and 6. The tabulating pins 14 are movably mounted in the

holes 13, the pins being of sufficient size and strength to withstand the impact of stopping the carriage in any position, and the entire series of pins comprise a number and arrangement whereby the carriage may be stopped in any adjustment or position within the scope of its travel. This enables the use of the tabulating mechanism for stopping the carriage at any point so that any desired sheet form will fit the machine and vice versa. Each pin 14 is provided with a flange 15 which serves as an abutment for the lower end of the encircling spring 16 whose upper end presses against the inner surface of the upper wall of the pin frame, or housing. The power of the springs 16 is exerted to press the pins toward idle position which is that position in which the upper end of the pins are substantially flush with the upper surface of the upper wall of the pin housing or frame. An annular flange 17 on each pin rests upon the lower wall of the pin housing or frame and constitute supports for the pins. The upper surface of the flanges 17 are beveled or inclined. A latch plate 18 is supported between the upper and lower walls of the housing or frame, the ends of said plate extending into openings in the ends of the housing or frame as shown at 19 in Figs. 2 and 6. A spring 20 (Figs. 2 and 6) connects the latch plate 18 with the supporting part and actuates said latch plate toward the left with respect to the operator. The pins 14 extend through round holes 21 in the latch plate 18. When the pins are in the idle or downward adjustment, the flanges 17 are below the latch plate and the flanges 15 are above the latch plate. When any pin is pressed upwardly, the beveled surface of the lower flange 17 will cause the latch plate to move laterally in opposition to its spring 20 until the larger part of the flange 17 enters the hole 21. Continued movement of the pin, so moving, will carry the flange 17 above the latch plate 18 at which time the spring 20 will restore the latch plate to its normal position which will latch the upraised or "set" pin in its new adjustment. Any pin previously raised or "set" will not be released by the "setting" of the second or any subsequent pin because the flanges or shoulders 17 are held in frictional engagement with the plate 18 and the pin so engaged will be carried along the length of the elongated holes 13 by the plate 18; while the pin passing to "set" position (Fig. 8) will be held at the opposite end of the holes 13 in which it is mounted. This lateral movement of the "set" pins, as effected by the plate 18, permits any number of pins to be adjusted and retained in operative or "set" adjustment without being released by operation or setting of other pins. This broadly elastic feature in the

setting of tabulating stops is an important part of the invention, particularly in view of the fact that a single selecting and "setting" device operates to set all of the stops.

The setting key 22 is arranged in convenient position in the key-board, being shown at the right in the present instance. The stem of said key is pivoted to a lever 23 (Fig. 3) which is upheld by a spring 24. A pin 25 is attached to the lever 23 and, in idle position, is above the plane of movement of a shoulder 26 on a link 27. The link 27 is provided with a slot 28 in its front end; and is supported by a screw or pin 29 passing through said slot. The link 27 extends toward the rear of the machine and is pivoted to an arm 30 attached to a rock shaft 31. Said rock shaft has another arm 32 attached thereto, preferably about midway of the sides of the machine. A vertical link 33 has its lower end pivoted to the arm 32. A transverse rod or shaft 34 supports a selecting or setting lever, pin driver or hammer 35 which extends forwardly under the pin frame or support 12. The pins 14 are carried over the member 35, the arrangement being such that the pins pass thereover in sequence, since the pins are arranged a single letter space apart. Operation of the lever 35 will drive or press upwardly that pin 14 which is above the said lever, and the pin so moved will be latched in its elevated adjustment by the latch plate 18 engaging under the flange or shoulder 17 on the pin. Only one pin will be raised at each operation of the member 35 for the reason that only one pin can be engaged by said member at any one operation. The lever or hammer 35 is held in its lower or idle adjustment by a spring 36 connecting the same with the frame of the machine. A shoulder 37 on said lever or driver engages with the machine frame, and constitutes a stop or an abutment for said lever or driver. The link 33 has a pin 38 extending into a slot 39 (Fig. 5) in the rear portion of the member 35, said pin normally being at the lower end of said slot. From the foregoing it will be clearly understood that depression of the "setting key" 22 will, through the connections shown (Fig. 3) and described, cause the hammer or driver lever 35 to "set" any pin 14 that may be positioned above said hammer or driver lever. The link 27 is also operable to release the carriage escapement devices and set the abutment against which the tabulating stops engage to stop the carriage. The tabulating key 40 is arranged in convenient position in the key-board, preferably close to the "setting key" so that the tabulating key may be readily operated after the "setting key" is operated. The stem of the tabulating key 40 is pivoted to a lever 41 to which is connected the

spring 24 which is effective to uphold the tabulating key as well as the setting key. Abutments 42 stop the two levers and keys in proper relative position. A pin 43 on the lever 41, normally above the plane of movement of a shoulder 44 on the link 27, will engage said shoulder when the key 40 is depressed and move the link 27 rearwardly. This operation raises the link 23. The pin 43 also extends into a slot 45 in the rear portion of a lever 46 which is pivoted upon the shaft 34, near the member 35. The lever 46 extends over a rod 47 carried by two arms 48 attached to a rock shaft 49, the rack 11 also being carried by said arms:

From the foregoing, and by reference to Fig. 3, it will be plain that the member 35 and the lever 46 are independently operable, and that each of said parts may be operated to perform its functions and duties without moving or disturbing the other, since the slots in said members are oppositely arranged.

A spring 50 upholds the front end of the lever 46. When the tabulating key 40 is operated, the front end of the lever 46 will press the rod 47 downwardly and raise the rack 11 out of mesh or entrained connection with the escapement mechanism, and permit the carriage to move laterally until stopped by the tabulating pins. For this purpose it is necessary that an abutment be provided and that said abutment be in position to be engaged by said pins. This abutment comprises a member 51 supported by the frame of the machine, and having two oblique slots 52 therein to receive the supporting studs 53. The abutment member is supported above the tabulating stops and requires downward movement before it can be engaged by said stops (Fig. 8). The lever 46 has an upwardly extending arm having a vertical slot 54 therein, and the member 51 has a horizontal slot 55 therein. A pin 56 extends through said slots, thereby forming a species of double slot-and-pin connection. A spring 57 connects the pin 56 with a stud 58 on the member 51, so that the lever 46 may operate and tension the spring 57 should downward movement of the member 51 be prevented by one of the pins 14. The carriage, however, will move since the rack 11 becomes disengaged from the escapement by the operation of the lever 46, and, as soon as the pin 14 moves from underneath the member 51 the latter will move obliquely downwardly and forwardly close to the upper wall of the pin support or housing 12 and constitute an abutment 60 for any following pin which is in "set" position. Release of the tabulating key permits the parts actuated thereby to return to normal or idle adjustments, and the rack 11 again to become enmeshed or entrained with the escapement mechanism. The scale 8,

with its pointer 8^a which is in alignment with the member 51, constitutes a guide to assist in determining which of the stops are to be set and in determining the width of the column spaces.

I have also provided convenient means for "clearing" the tabulating stops. A lever 59 is supported on a stud 60 attached to one wall of the stop support or housing. Said lever has an opening 61 therein, and a cam surface 62 formed by the inner wall of said opening. A pin 63 attached to the latch plate 18 projects into said opening 61. By drawing forwardly the outer end of the lever 59 the cam surface 62 will rub against the pin 63 and draw laterally the plate 18 the full distance required to register the holes 21 in said plate with the flanges 17, which will release all of the pins and permit them to be pressed down by their encircling springs 16. This "clears" the pins and permits them to be readjusted to suit any desired form or sheet.

The pin frame or housing is removably secured to the carriage by screws 64, so that said frame may readily be removed for purposes of repair, readjustment, etc.

By use of my invention the carriage may be stopped in any of its letter space positions. But it should be understood that any less number of stops may be employed. The single train of actuating devices leading from the "setting key" and from the tabulating key and the convenient and compact arrangement of these parts are important features and advantages over other tabulating mechanisms.

I am aware that there may be many changes and variations in the construction and arrangement of the parts without departing from the spirit and scope of my invention. I do not restrict myself to identical features but

What I claim and desire to secure by Letters Patent is—

1. In a tabulating mechanism, the combination of a series of column stops movable into and out of operative position, springs pressing said stops in one direction, means for moving said stops to operative position, a latch device holding said stops in operative position, and a lever operable to move and disengage said latch device from said stops to release said stops.

2. In a tabulating machine, the combination of a series of column stops movable individually into operative position, springs pressing said stops toward idle position, means for latching said stops in operative position, and means for moving said latch device effectively to release all stops latched thereby.

3. In a tabulating mechanism, the combination of a series of column stops movable into and out of operative position and

- spring-pressed to inoperative position, means for holding said stops against the spring pressure thereon, and a lever for releasing all of said stops at a single operation.
4. In a tabulating mechanism, the combination with the carriage, the frame, and an escapement mechanism for said carriage, of an abutment, a series of column stops, 10 springs pressing said stops toward idle position, means for latching said stops in operative position, means for disconnecting said escapement mechanism and adjusting said abutment in position to be engaged by 15 said stops and a lever operable to move said latching means and release all of said stops.
5. In a tabulating mechanism, the combination of a support, stop pins mounted in 20 said support, springs pressing said pins in one direction, manipulative means for moving said stops in opposition to said springs, and a latch device effective to hold any number of said pins in opposition to said 25 springs, said latch device being movable by said pins when said pins move in opposition to said springs.
6. Tabulating mechanism comprising movable stop pins, a latch device, a spring 30 holding said latch device, and mechanism for moving said pins and said latch device relatively effectively to latch and retain pins in operative adjustment while others of said 35 pins and said latch device are operated to latched adjustment, substantially as specified.
7. Tabulating mechanism comprising a support having elongated holes therein, a latch plate having holes therein, pins mounted in said holes and being capable of lateral movement therein, and means for causing any desired number of said pins to become latched with said latch plate.
8. Tabulating mechanism comprising a 45 support, laterally and vertically movable pins mounted in said support, a latch plate, a spring holding said latch plate, and means for operating said pins effectively to cause any desired number thereof to engage said latch plate.
9. In a tabulating mechanism, the combination of stop pins, a device for moving said stop pins to operative adjustment, an abutment, connections operable in one direction to move said "device" and in the other direction to move said abutment to operative position, and two keys operable to cause said connections to operate, substantially as specified.
10. A tabulating mechanism comprising tabulating pins, a driver for "setting" said pins, an abutment for said pins, a "setting" key, a tabulating key, and connections controlled by said "setting" key effectively to operate said driver, and by said tabulating key effectively to operate said abutment.
11. A tabulating mechanism comprising, in combination with a carriage, a series of tabulating pins, an abutment, a train of connected devices for operating said pins and 70 said abutment, a key for operating said connected devices effectively to operate said pins, and a separate key for operating said devices effectively to operate said abutment.
12. A tabulating mechanism comprising 75 a support, pins mounted in said support, a spring-held latch plate carried by said support, and a key operable to move said pins and thereby said latch plate into interlocked engagement.
13. A tabulating mechanism, comprising a support, pins mounted in said support, a latch plate carried by said support, a key operable to move said pins and thereby said latch plate into interlocked engagement, and 85 manipulative means for releasing said latch plate from said engagement with said pins.
14. The combination with a carriage movable laterally for column spacing, of tabulating mechanism comprising a series of 90 tabulating stop pins, a latch plate for said pins, means for moving said pins and thereby said latch plate into interlocked engagement, an abutment, and a key operable to set said abutment and permit said carriage 95 to move.
15. Combination with a carriage movable laterally for column spacing, and an escapement device controlling said carriage, of a series of stop pins, a latch device for said 100 pins, means for moving said latch device and pins into interlocked engagement, an abutment for said pins, and a key operable to move said abutment into operative adjustment and to release said escapement device. 105
16. In a tabulating mechanism, a housing comprising upper and lower walls, having holes therein, a latch plate between said walls, pins mounted in said holes, and mechanism for interlocking said pins and latch 110 plate.
17. In a tabulating mechanism, a housing having upper and lower walls having holes therein, a latch plate mounted between said walls, pins mounted in said holes, a driver 115 operable to interlock said pins with said latch plate, and a lever for releasing said plate from said pins.
18. In a tabulating mechanism, the combination of a frame, a series of column stops 120 in said frame adapted to be moved into and out of operative position, springs pressing said stops out of operative position, a lever for moving said stops into operative position, a latch device mounted in said frame 125 for holding said stops in operative position, and means for releasing said latch device, substantially as specified.

19. In a tabulating mechanism, the combination of a frame, a series of column stops mounted in said frame and adapted to be moved individually into operative position, a spring encircling each of said stops for actuating the same toward idle position, a lever, key connections for operating said lever to move said stops individually into operative position, a latch device in said frame for holding said stops in operative position, and a lever for moving said latch device to release all stops held thereby, substantially as specified. 70
20. In a tabulating mechanism, the combination of a series of column stops movable into and out of operative position, springs pressing said stops to inoperative position, a latch plate for holding said stops in operative position, a lever, and connections between said lever and said latch plate whereby said latch plate may be moved to release all of said stops at a single operation, substantially as specified. 75
21. In a tabulating mechanism, the combination with the carriage, the frame, and an escapement mechanism for said carriage, of a series of column stops mounted in the carriage, springs pressing said stops toward idle position, a sliding latch plate whereby said stops may be latched in operative position, an abutment for said stops, means for disconnecting said escapement mechanism and adjusting said abutment in position to be engaged by said stops, and means for releasing all of said stops at a single operation, substantially as specified. 80
22. In a tabulating mechanism, the combination of a stop frame, stop pins mounted in said frame, springs pressing said pins in one direction, a key, connections operated by said key for moving said pins in opposition to said springs, a latch plate in said support effective to hold any number of said pins in opposition to said springs, said latch plate being movable by said pins when said pins move in opposition to said springs, and an abutment movable into and out of the path of said pins, substantially as specified. 85
23. Tabulating mechanism comprising movable stop pins, a latch plate for said pins, a spring holding said latch plate, mechanism for moving said pins and thereby said latch plate relatively effectively to latch and retain the pins in operative adjustment while others of said pins are operated to latched engagement with said latch plate, an abutment movable into and out of the path of said pins, and a lever for releasing all of said pins at a single operation, substantially as specified. 90
24. Tabulating mechanism comprising a support having elongated holes therein, a latch plate having holes therein, pins mounted in said holes and being capable of lateral movement therein, springs actuating said pins to idle position, a lever, and means for operating said lever to cause any desired number of said pins one at a time to become latched with said latch plate, substantially as specified. 95
25. Tabulating mechanism comprising a support, laterally and vertically movable pins mounted in said support, springs for actuating said pins to idle position, a sliding latch plate mounted in said support, a spring holding said latch plate in one position, a lever, a link connected to said lever, and a key for operating said lever effectively to cause any desired number of said pins one at a time to engage with said latch plate, substantially as specified. 100
26. In a tabulating mechanism, the combination of stop pins, a device for moving said stop pins to operative adjustment, an abutment, means holding said abutment in idle position, connections operable in one direction to move said "device" and in the other direction to move said abutment to operative position, a key for operating said connections to move said abutment, and a separate key for operating said connections to move said "device" as aforesaid, substantially as specified. 105
27. A tabulating mechanism comprising tabulating pins, a pivoted lever for setting said pins, means for holding said lever out of engagement with said pins, an abutment for said pins, means holding said abutment out of the path of movement of said pins, connections from said pivoted lever, a key for operating said connections and said lever to set said pins, and a separate key for operating said connections to move said abutment into the path of movement of the pins which have been set, substantially as 110 specified. 115
28. The tabulating mechanism comprising a carriage, a series of tabulating pins supported by said carriage, a movable abutment, a lever for operating said abutment, a separate lever for operating said pins, a single train of connections for operating said two levers, a key for operating said connections effectively to operate said pins, a separate key for operating said connections effectively to operate said abutment, and means for restoring said connections and said keys to idle position, substantially as specified. 120
29. A tabulating mechanism, comprising upper and lower walls, pins supported by said walls, a latch plate mounted between said walls, a spring for holding said latch plate in one position, a key operable to move said pins and thereby said latch plate into interlocked engagement, a lever supported independently of said latch plate, and means whereby operation of said lever will operate said latch plate to release all of said pins, substantially as specified. 125

30. A tabulating mechanism, comprising an upper wall and a lower wall both provided with holes, pins mounted in said holes, a latch plate between said walls, shoulders 5 on said pins, springs actuating said pins to idle position, a key for moving said pins to engage said shoulders with said latch plate, a lever supported by one of said walls and means whereby operation of said lever will 10 move said latch plate to release said shoulders therefrom, substantially as specified.

31. The combination with a carriage movable laterally for column spacing, of two parallel walls mounted in said carriage, a series 15 of tabulating stop pins supported by said walls, a latch plate for said pins, a spring actuating said latch plate in one direction, a lever, a key, connections whereby said key will operate said lever effectively to move 20 said latch pins and thereby said latch plate into interlocked engagement, an abutment for said pins, and a lever for moving said latch plate to release said pins therefrom, substantially as specified.

32. The combination with a carriage movable laterally for column spacing, and an escapement device controlling said carriage in its lateral movement, of a series of stop pins mounted in said carriage, springs actuating said stop pins to idle position, a latch 30 device for said pins in said carriage, key connections for moving said latch device and pins into interlocked engagement, an abutment for said pins supported independently of said carriage, means for holding 35 said abutment in inoperative adjustment, and a lever operable to move said abutment into operative adjustment and to release said escapement device, substantially as specified. 40

In witness whereof, I have signed this specification in the presence of two subscribing witnesses.

HARRY LANDSIEDEL.
